UNITED STATES PATENT OFFICE.

JOHN THOMAS BAKER, OF BALTIMORE, MARYLAND.

GAS-FIXTURE.

1,113,862.

Specification of Letters Patent. Patented Oct. 13, 1914.

Application filed April 26, 1912. Serial No. 693,356.

To all whom it may concern:

Be it known that I, JOHN T. BAKER, a citizen of the United States, residing at Baltimore, in the State of Maryland, have invented new and useful Improvements in Gas-Fixtures, of which the following is a specification.

This invention relates to gas fixtures and more particularly to that type which are used in connection with heating systems.

The principal object of the invention is to provide a device which will obviate the many disastrous accidents caused by accidentally turning off the gas. Devices of this character have been devised before but their parts were so complicated or expensive that their use was prohibited.

It is, therefore, another object of this invention to provide a cheap and efficient structure of this type which will insure proper locking of the cock in open or closed position.

Further objects of this invention will appear as the following specific description is read in connection with the accompanying drawings, which form a part of this application, and in which:

Figure 1 is a perspective view of a gas heating fixture showing my invention applied thereto. Fig. 2 is a top plan view thereof showing the valve in open position. Fig. 3 is a section on the line 3—3 of Fig. 2 showing the valve in closed position. Fig. 4 is a top plan view showing a modification. Fig. 5 is a perspective view of the lock shown at Fig. 4.

Referring to the drawing, and more particularly to Figs. 1 and 3, 1 represents an ordinary gas supply pipe which has connected to it the outlet or discharge pipe 2 having a valve casing 3 arranged within its length, as shown. This casing has the ordinary valve 4 mounted therein which is operated by the handle 5. Projecting horizontally from adjoining sides of the valve stem are locking pins 6 which are adapted to engage in the aperture 7 formed upon the locking member 8 which is in the form of a leaf spring permanently secured by means of the rivet 9 to the casing 3. Extending laterally from the head of the spring and on opposite sides of the aperture 7 are guiding fingers or flanges 10 which are adapted to be engaged by the pins 6 to move the same away from engagement with the stem and thereby permit easy access of the pin into the ap-

erture. The upper end of the spring is provided with a thumb piece 11 by which the same may be disengaged from the pins when it is necessary to turn the valve to either open or closed position. It will be understood that with the present device, all that is necessary is to disengage the spring from one of the pins and then release the same. The turning of the handle will bring the other pin into engagement with one of the flared flanges 10, thereby displacing the spring until the pin alines with the aperture 7 therein, at which time the locking member 8 will spring into locking engagement with the pin and prevent further movement of the valve. With this type of valve, the usual stop pins are found to be unnecessary as the valve when turned is not only stopped into fully closed or open position but is also locked in such position.

In the modification shown in Figs. 4 and 5, one pin only is used, the same being indicated at 12. The spring in this instance is shown at 13 and is secured to the valve casing 3 in the manner shown in Figs. 1 and 2. The upper end thereof is provided with an aperture 14 to engage the pin and with a laterally curved finger 15 having a flared end 16 to guide the pin into an aperture 17 which when engaged with the pin, locks the valve in open position. The upper end of the pin is also provided with a thumb piece 18.

What is claimed is:—

1. In a locking device for gas valves, the combination with a valve casing having a rotary valve stem therein, a handle fixedly mounted upon said stem and lying above the casing, a locking pin carried by said stem and extending radially therefrom, of a spring carried by the casing and having a free portion bearing against one end of the handle and apertured for the reception of the pin on a predetermined adjustment of said handle, and means extending laterally from the free end of the spring and disposed in the path of travel of the pin and adapted to be engaged by the latter during rotation of the handle, whereby to disengage the free end of the spring from the end of the handle, to permit the pin to enter the aperture in the spring upon the required adjustment of the handle, and a manipulating extension formed on the said free end of the spring and extending normally at an acute angle thereto and lying above the handle, and

adapted to be engaged by the hand of the operator so as to permit lateral pressure of the hand to effect the release of the spring from the pin to permit the handle to be operated.

2. In a locking device for gas valves, the combination with a valve casing having a rotary valve stem therein, a handle fixedly mounted upon said stem and lying above the 10 casing, and a locking pin carried by said handle and extending radially therefrom, of a spring having one end fixedly secured to the casing and its free end bearing against one end of the handle and apertured for 15 the reception of the pin on a predetermined adjustment of the said handle, said free end of the spring having a concavo-convex portion extending laterally therefrom and disposed in the path of travel of the pin and 20 adapted to be engaged by the latter during

rotation of the handle whereby to disengage the free end of the spring from the end of the handle to permit the pin to enter the aperture in the spring upon the required adjustment of the handle, and a manipulating 25 extension formed on the free end of the spring and disposed above the said concavo-convex portion and above the handle, and adapted to be engaged by the hand of the operator to permit lateral pressure of the 30 hand to effect the release of the pin from the spring, to permit the handle to be operated.

In testimony whereof I affix my signature in presence of two witnesses.

JOHN THOMAS BAKER.
